UNITED STATES PATENT OFFICE.

DAVID PATASNIK, OF BROOKLYN, NEW YORK.

DESIGN FOR A WINDOW SASH.

Application filed June 25, 1926. Serial No. 18,185. Term of patent 14 years.

To all whom it may concern:

Be it known that I, DAVID PATASNIK, a citizen of the United States, residing at Brooklyn, in the county of Kings and State of New York, have invented a new, original, and ornamental Design for Window Sash, of which the following is a specification, reference being had to the accompanying drawing, forming part thereof.

The figure is a perspective view of a window sash, showing my new design.

I claim:—

The ornamental design for a window sash, as shown.

DAVID PATASNIK.
